UNITED STATES PATENT OFFICE.

ANTON ZEMAN, OF CAMDEN, NEW JERSEY, AND GEORGE W. NEMEC, OF PHILADELPHIA, PENNSYLVANIA; SAID NEMEC ASSIGNOR TO SAID ZEMAN.

ADJUSTABLE WINDOW SCREEN.

Application filed December 11, 1920. Serial No. 429,941.

To all whom it may concern:

Be it known that we, ANTON ZEMAN and GEORGE W. NEMEC, citizens of Czechoslovakia and the United States, respectively, 5 residing at Fairview and Philadelphia, respectively, in the counties of Camden and Philadelphia, respectively, and States of New Jersey and Pennsylvania, respectively, have invented new and useful Improvements 10 in Adjustable Window Screens, of which the following is a specification.

This invention relates to window screens, and it has more particular reference to that type or form of device which includes a 15 casing that houses a spring influenced screen or curtain roller which is adapted for connection to and movement simultaneously with the raising or lowering of a window-sash, said mechanism having associated therewith means whereby the opening to the atmosphere is protected from incoming dust, dirt, vermin, flies or the like.

Another object of this invention is to provide a novel form of window screen which 20 may readily be fitted to any window frame for either temporary or permanent use.

With the foregoing and other objects in view as will later on be more apparent this invention consists essentially in making 30 the screen telescopic or adjustably adaptable for fitment to windows of different width, and in the novel features of construction, combination and arrangements of parts hereinafter fully described, and more 35 specifically defined by the appended claims.

In the further disclosure of the invention reference is to be had to the accompanying sheets of explanatory drawings, constituting a part of this specification, and in which 40 similar characters of reference denote the same or corresponding parts in all the views.

Figure 1 is a fragmentary front elevation of a portion of a window frame and lower sash having my improved window 45 screen fitted thereto.

Figure 2 is a vertical section of the same and taken approximately on the line 2-2 in Figure 1.

Figure 3 is a longitudinal section through 50 the telescopic casing for the screen, and is taken on the line 3-3 in Figure 1.

Figure 4 is a transverse section on the line 4-4 in Figure 3.

Figure 5 is a transverse section on the 55 line 5-5 in Figure 3.

Figure 6 is a transverse section on the line 6-6 in Figure 3.

Figure 7 is an end elevation of the telescopic casing for the screen with a portion of one of the grooved side members or 60 brackets hereinafter more particularly referred to.

Figure 8 is a fragmentary perspective elevation of the lower portion of one of the grooved side members. 65

Figure 9 is an enlarged sectional detail taken approximately on the line 11-11 in Figure 1, and looking to the left hand thereof; and

Figure 10 is a similar enlarged sectional 70 detail taken approximately on the line 12-12 in Figure 1, and likewise looking towards the left hand thereof.

Referring to the drawings the numeral 13 designates a fragmentary portion of the 75 lower structure of a window including a sash 14, said window having the usual sill 15 and the side stiles or frames 16, and said sash 14 being mounted to slide vertically therein in the usual well known way. 80 Adapted for disposition horizontally across the sill 15 is a casing or box-like structure 17 which comprises opposed end telescopic sections 18, 18, and an intermediate section 19, said casing 17 being preferably made of 85 thin sheet metal bent or otherwise formed to the U-shape shown in Figures 4 to 7, more particularly. This casing or box-like structure 17 also includes end members or walls 20 which are similarly stamped from sheet 90 metal and are provided with outwardly projecting ears and a channel shaped flange 21, 22, respectively, which serve as a means whereby the end sections may be connected thereto as by rivets 23 whilst the back or 95 web of the latter 22 forms a seat for the back wall 24 which is similarly secured thereto by rivets 25. It is also to be here noted that the upper longitudinal edge of each end section 18 is rolled or turned over 100 at 26 to constitute a guide for the similarly rolled or turned over upper beaded edge 27 of the intermediate section 19, or in other words the beaded edge 27 is adapted for telescopic engagement in the correspondingly beaded edges 26 of both end sections 18 as will be clearly understood on an inspection of the drawings. In like manner 105 the lower edge of the intermediate section 19 is turned over into substantially U-shaped 110

cross section to constitute a guide or runner 28 for co-operation with the lower edge of the end sections 18.

The back wall 24, similarly comprises end 5 or telescopic sectional members 29, 29, and a medial member 30, the latter being of substantially L-shape in cross-section, that is to say it is formed with a lower longitudinal angled edge 31. On the other hand the end 10 members 29, 29, are turned over at their upper longitudinal edges to form U-shaped guides 32 for engagement over the upper longitudinal edge of the medial member 30, whilst the lower longitudinal edges are 15 turned over to constitute U-shape runners 33 for the lower angled edge 31 of the aforesaid medial member. It is also to be particularly noted that the inner lower U-shaped runners 33 are cut at 34—Figure 3—and 20 downwardly stepped to provide ears or gripping members 35 which engage beneath the lower turned over edge of the intermediate casing section 19.

Rotatably mounted in a journal 36 longitudinally of the aforesaid casing 17 is a spring-influenced shade roller 37 to which is attached the inner end of a reticulated or wire mesh screen or curtain 38 which is adapted to be drawn up out of said casing 30 17 through the aperture or slot 39 provided between the front or U-shaped walls and the back wall 24 as will be clearly understood on an inspection of Figure 2 more particularly. This roller 37 is of the well known shade roller type but is provided at 35 the spring actuated end with an improved construction of cap-piece 40 which eliminates the employment of nails or wire brads for its attachment, and to this end I form 40 said cap-piece 40 with inwardly protecting prongs 41 which engage in the end of the wooden roller 37. Longitudinally projecting from the outer end of the cap-piece 40 are a plurality of opposed teeth or tongues 45 42 of segmental cross section as will be clearly seen on an examination of Figure 6, and said teeth or tongues 42 being adapted to be engaged by a retaining dog or finger operably locking-pawl 43 which is pivoted 50 at 44 on the adjoining end wall 20 and fashioned with a finger hold or key piece 45 that projects through a slot 46 provided for the purpose in the end section 18. The shade roller influencing spring is anchored 55 at its outer end by a projecting pin or axle 47 which is engaged in a T-shaped slot 48 formed for its reception in the adjoining end wall 20.

It is also to be particularly noted that 60 in connection with the aforesaid side uprights 49 we bead or roll the lower frontal edge of the wall 52 at 69, said bead or roll being adapted to engage the upper rolled over or beaded edges 26 on the end sections 18, whilst the other wall 51 of said uprights

is downwardly extended at 70 and formed with a turned over ear or tongue 71 which when the parts are assembled clips over or engages snugly on the channel shaped flange 22 on the adjoining end wall 20 hereinbefore described, said assemblage of parts being clearly discernible from Figures 3 and 7 more particularly. In order to strengthen the inner and outer edges of the spaced walls 51, 52, we preferably roll the 75 edges upon themselves as shown at 72.

Connected in any appropriate manner with the upper longitudinal edge of the reticulated screen or curtain 38 is a rod 73 housed in a seamed or longitudinally split tube 74 which is telescopically mounted in the rolled or beaded edges 75 of opposed sections 76 of substantially tubular formation in cross section as shown, to an enlarged scale in Figure 11. These sections 80 76 are each preferably made from a strip of sheet metal folded longitudinally upon itself at 77, one of said folded over parts being then rolled along the edge to provide the aforesaid bead 75, whereas the other 90 folded over part is bent at right angles to provide a laterally projecting limb or strip 78, which is in turn folded upon itself and downwardly inclined at 79 for the purpose later on explained. It is also to be observed 95 that these sections 76 are cut-away at their outer ends 80 in so far as the laterally projecting strips 78 are concerned so that the vertically disposed portions 77 may ride freely up and down the grooves or guides 100 53, and it is to be noted that when the screen or curtain 38 is rolled up on the roller 37 these sections will to a great extent close in the slot 39 and thereby effectively prevent the ingress of dirt, rain and the like into 105 the casing 17.

Stamped or otherwise pressed-up from the lateral limb 78 of each section 76 is a turned-over ear 81 which forms a pivot for a bayonet or T-shaped eyelet or ring 82 110 which in use may be hooked on to one of the sash raising handles—or preferably is adapted to engage a screw 83 provided for the purpose in the bottom rail 84 of the sash 14, whereby said sash 14 and the screen or curtain 38 may be raised or lowered simultaneously; in other words the aforesaid eyelets or rings 82 serve the purpose of causing the screen or curtain to cover the opening when the sash 14 is raised.

In some instances and where it may be desirable to give additional support to the screen 38 as in the case of very wide windows we may employ an additional centrally located support 85 which consists of a strip of metal folded upon itself as shown clearly in Figure 12, and formed to provide springy gripping jaws 86 which can be clamped over the hereinbefore described split-tube 74 by 125 means of a wood screw 87 being driven into 130

the bottom rail 84, and as will be clearly apparent to those skilled in the art to which this invention appertains.

Assuming that our improved window screen constructed and assembled as hereinbefore is installed in a window 13 as shown by Figures 1 and 2, it will be readily seen that when it is desired to raise the lower sash 14 a distance for purposes of ventilation, and that in doing so it is desired that the opening formed by the raising of said sash be properly screened to prevent the entry of insects and the like, and that the ventilation will be such as not to cause a direct draft into the room and further help to keep out any inclement weather such as rain, sleet or snow; to accomplish said results the T-shaped eyelets hingedly attached to the opposed rail sections 76 are firstly hooked on to the screws 83 in the bottom rail of the sash 14, either before or after the said sash is raised, thus causing the screen 38 to be unwound from the spring roller 37 and pulled out of the box-like casing 17 through the slot 39 therein and thus covered the opening made by the raising of the lower window sash. In this position it will be readily seen that the window opening created by the raising of the lower sash 14 will be effectively screened to prevent the entry of any insects or the like, and that adequate ventilation will be provided. When the window is of considerable width it will be obvious that the centrally located support 85 may be connected up as hereinbefore described whereby the screen or curtain 38 will be prevented from sagging or bulging and be kept in snug alignment over the opening created by the raising of the lower sash 14. On closing down the lower sash 14 it will of course be understood that the locking pawl 43 will be released by a pressure on the finger piece or key 45, so that the spring in the roller 37 will wind up the screen or curtain 38, and thereby return said screen or curtain automatically back into the box-like casing 17.

From the foregoing description and an examination of the drawings it will be readily seen that by our invention we provide a strong, serviceable, light and very effective combined window screen and ventilator which is readily adjustable to windows of different widths due to the telescopic construction of the box-like casing 17 and its back wall 24, all that is necessary being to procure a roller 37, a screen or curtain 38 of proper length, and we wish particularly to emphasize the fact that we do not in any way limit ourselves to the use of the combined window screen and ventilator at the bottom of a window, as it will be self-evident that with very minor detail changes it can be equally well installed at the top of a window and made operable with the upper

sash. Furthermore it is to be noted that a window screen and ventilator of the type described is of very simple construction and cannot get out of order, whilst it provides an efficient means for ventilating a room or apartment without the risk of bad and unhealthy drafts or the ingress of insects and atmospheric changes or conditions.

It will also be apparent that by making the box-like casing adjustable a great saving can be effected, and greater efficiency ensured as the entire appliance can be far more accurately fitted into the window frame or casing 17 as will be obvious to those acquainted with the art to which our invention appertains. A still further advantage accruing to our appliance is that by the use of a very fine reticulated screen or curtain 38, or the use of a fabric screen, the entering air passing therethrough will be filtered or freed from dust and the like, whilst if said screen or curtain 38 is impregnated with an appropriate disinfectant foul gases carried by said incoming air can be sterilized and thoroughly purified before circulating in the room or apartment.

Finally we wish it clearly understood that whilst we have described and shown the best form of our invention at present known to us we do not restrict ourselves to the precise details of construction, combination and arrangement of parts disclosed, but deem ourselves at liberty to make such changes and other arrangements of the several parts as may be reasonably construed as falling within the scope of the appended claim.

Having described our invention what we claim as new and desire to secure by Letters Patent is:—

The combination with a window frame of a sash slidably mounted therein, a substantially tubular casing transversely mounted within said frame, said casing having a longitudinal screen opening and comprising, end sections of substantially U-shaped cross section with the upper and lower edges thereof beaded for longitudinal slidable adjustment, and an intermediate section of similar shape and correspondingly beaded for slidable longitudinal adjustment in relation to said end sections, transversely disposed end walls closing the opposite ends of said casing, laterally projecting ears on said end walls engaging the casing end sections, means adapted to securely fasten said ears to the end sections, a back wall longitudinally slidably mounted on said casing, said back wall comprising end sections turned over on one edge to form substantially U-shaped guides for longitudinal adjustment, and an intermediate section of substantially L-shaped cross section adapted for longitudinal adjustment in relation to said back wall end sections, a spring influenced roller rotatably mounted within said casing, a

screen mounted on said roller adapted to be withdrawn from or redrawn into said casing thereby, uprights of substantially L-shaped cross section attached to opposite sides of the window frame, a downwardly extended wall on said upright provided with a hooked ear portion, a second wall adjacent the first mentioned wall spaced therefrom and having its lower end beaded, said hooked ear portion and beaded portion of said walls being adapted to clamp the end sections of the casing to the uprights, means

adapted to detachably clamp the free end of said screen to said slideable window sash, manually controlled latch means adapted to restrain and lock said roller against back motion when said screen is withdrawn from the casing or be released and thereby unlock said roller for back motion when desired.

In testimony whereof we affix our signatures.

ANTON ZEMAN.
GEORGE W. NEMEC.
